UNITED STATES PATENT OFFICE.

HERMAN IHLENBURG, OF PHILADELPHIA, PENNSYLVANIA, ASSIGNOR
TO THE AMERICAN TYPE FOUNDERS COMPANY, OF NEWARK, NEW
JERSEY.

DESIGN FOR A FONT OF PRINTING-TYPE.

SPECIFICATION forming part of Design No. 24,896, dated November 12, 1895.

Application filed December 22, 1893. Serial No. 494,473. Term of patent 7 years.

To all whom it may concern:

Be it known that I, HERMAN IHLENBURG, a citizen of the United States, residing in Philadelphia, Pennsylvania, have invented a certain Design for Type, of which the following is a specification.

My design for a font of ornamental printing-type is clearly shown in the annexed typographical impression, which illustrates the type of the upper case, the lower case, and the numerals.

The main feature of the design is the unevenness of the lines of the type, giving the peculiar effect shown, and provided with a medium heavy face, the characters being

plain and the lines of each character having uneven undulating edges. This unevenness is not only found in the upper-case type, but also in the lower-case type and the numerals.

I claim—

The design for a font of printing type as herein described and shown in the accompanying typographical impression.

In testimony whereof I have signed my name to this specification in the presence of 25 two subscribing witnesses.

HERMAN IHLENBURG.
